UNITED STATES PATENT OFFICE

163,115

PICKUP TOY

Percy J. Gordineer, Niagara Falls, N. Y.

Application June 18, 1948, Serial No. 147,062

Term of patent 14 years

(Cl. D34—15)

To all whom it may concern:

Be it known that I, Percy J. Gordineer, a citizen of the United States of America, residing in Niagara Falls, county of Niagara, State of New York, have invented a new, original, and ornamental Design for a Pickup Toy, of which the following is a specification, reference being had to the accompanying drawing forming a part thereof.

The figure is a perspective view of a pickup toy showing my new design.

Both sides of the design are identical.

I claim:

The ornamental design for a pickup toy, substantially as shown and described.

PERCY J. GORDINEER.
